CLAIM

The ornamental design for a shape transforming toy assembly, as shown and described.

DESCRIPTION

FIG. 1 is the first perspective view of a shape transforming toy assembly in an assembled configuration, showing my new design;

FIG. 2 is a front view of FIG. 1;

FIG. 3 is the second perspective view in a second assembled configuration;

FIG. 4 is a front view of FIG. 3;

FIG. 5 is the third perspective view in a third assembled configuration;

FIG. 6 is a front view of FIG. 5;

FIG. 7 is a perspective view of the first part in the transforming configuration thereof, shown separately for ease of disclosure;

FIG. 8 is a perspective view of the first part in the transforming configuration thereof;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view of the second part in the transforming configuration thereof, shown separately for ease of disclosure;

FIG. 16 is a perspective view of the second part in the transforming configuration thereof;

(Continued)

FIG. 17 is a front view thereof;
 FIG. 18 is a rear view thereof;
 FIG. 19 is a left side view thereof;
 FIG. 20 is a right side view thereof;
 FIG. 21 is a top plan view thereof;
 FIG. 22 is a bottom plan view thereof;
 FIG. 23 is a perspective view of the third part in the transforming configuration thereof, shown separately for ease of disclosure;
 FIG. 24 is a perspective view of the third part in the transforming configuration thereof;
 FIG. 25 is a front view thereof;
 FIG. 26 is a rear view thereof;
 FIG. 27 is a left side view thereof;
 FIG. 28 is a right side view thereof;
 FIG. 29 is a top plan view thereof;
 FIG. 30 is a bottom plan view thereof;
 FIG. 31 is a perspective view of the fourth part in the transforming configuration thereof, shown separately for ease of disclosure;
 FIG. 32 is a perspective view of the fourth part in the transforming configuration thereof;
 FIG. 33 is a front view thereof;
 FIG. 34 is a rear view thereof;
 FIG. 35 is a left side view thereof;
 FIG. 36 is a right side view thereof;
 FIG. 37 is a top plan view thereof;
 FIG. 38 is a bottom plan view thereof;
 FIG. 39 is a perspective view of the fifth part in the transforming configuration thereof, shown separately for ease of disclosure;
 FIG. 40 is a perspective view of the fifth part in the transforming configuration thereof;
 FIG. 41 is a front view thereof;
 FIG. 42 is a rear view thereof;
 FIG. 43 is a left side view thereof;
 FIG. 44 is a right side view thereof;
 FIG. 45 is a top plan view thereof;
 FIG. 46 is a bottom plan view thereof;
 FIG. 47 is a perspective view of the sixth part in the transforming configuration thereof, shown separately for ease of disclosure;
 FIG. 48 is a perspective view of the sixth part in the transforming configuration thereof;
 FIG. 49 is a front view thereof;
 FIG. 50 is a rear view thereof;
 FIG. 51 is a left side view thereof;
 FIG. 52 is a right side view thereof;
 FIG. 53 is a top plan view thereof;
 FIG. 54 is a bottom plan view thereof;
 FIG. 55 is a perspective view of the seventh part in the transforming configuration thereof, shown separately for ease of disclosure;
 FIG. 56 is a perspective view of the seventh part in the transforming configuration thereof;
 FIG. 57 is a front view thereof;
 FIG. 58 is a rear view thereof;
 FIG. 59 is a left side view thereof;
 FIG. 60 is a right side view thereof;
 FIG. 61 is a top plan view thereof;
 FIG. 62 is a bottom plan view thereof;
 FIG. 63 is a perspective view of the eighth part in the transforming configuration thereof, shown separately for ease of disclosure;

FIG. 64 is a perspective view of the eighth part in the transforming configuration thereof;
 FIG. 65 is a front view thereof;
 FIG. 66 is a rear view thereof;
 FIG. 67 is a left side view thereof;
 FIG. 68 is a right side view thereof;
 FIG. 69 is a top plan view thereof;
 FIG. 70 is a bottom plan view thereof;
 FIG. 71 is a perspective view of the ninth part in the transforming configuration thereof, shown separately for ease of disclosure;
 FIG. 72 is a perspective view of the ninth part in the transforming configuration thereof;
 FIG. 73 is a front view thereof;
 FIG. 74 is a rear view thereof;
 FIG. 75 is a left side view thereof;
 FIG. 76 is a right side view thereof;
 FIG. 77 is a top plan view thereof;
 FIG. 78 is a bottom plan view thereof;
 FIG. 79 is a perspective view of the tenth part in the transforming configuration thereof, shown separately for ease of disclosure;
 FIG. 80 is a perspective view of the tenth part in the transforming configuration thereof;
 FIG. 81 is a front view thereof;
 FIG. 82 is a rear view thereof;
 FIG. 83 is a left side view thereof;
 FIG. 84 is a right side view thereof;
 FIG. 85 is a top plan view thereof; and,
 FIG. 86 is a bottom plan view thereof.

The broken lines shown in the drawings illustrate portions of the shape transforming toy assembly that form no part of the claimed design.
